(57) **CLAIM**

The ornamental design for a reflective pet wear, as shown and described.

DESCRIPTION

FIG. 1 is a front elevational view of the reflective pet wear showing my new design;

FIG. 2 is a rear elevational view of the reflective pet wear of FIG. 1;

FIG. 3 is a left side elevational view of the reflective pet wear of FIG. 1;

FIG. 4 is a right side elevational view of the reflective pet wear of FIG. 1;

FIG. 5 is a top plan view of the reflective pet wear of FIG. 1;

FIG. 6 is a bottom plan view of the reflective pet wear of FIG. 1; and,

FIG. 7 is a rear elevational view of a second embodiment of the reflective pet wear showing my new design, it being understood that the only difference from the other embodiment resides in the LED lights.

The broken lines showing of a dog in FIGS. 1 and 7 are for illustrative purposes only and form no part of the claimed design.
